UNITED STATES PATENT OFFICE.

WILLIAM M. SMITH AND PAUL W. SMITH, OF OELWEIN, IOWA.

SCREEN-DOOR SHOO-FLY ATTACHMENT.

Application filed October 18, 1921. Serial No. 508,572.

To all whom it may concern:

Be it known that we, WILLIAM M. SMITH and PAUL W. SMITH, citizens of the United States, residents of Oelwein, in the county 5 of Fayette and State of Iowa, have made a certain new and useful Invention in Screen-Door Shoo-Fly Attachments; and we declare the following to be a full, clear, and exact description of the same, such as will enable 10 others skilled in the art to which it appertains to make and use the invention, reference being had to the accompanying drawings, and to letters or figures of reference marked thereon, which form a part of this 15 specification.

Figure 1 is a side view of the invention, as applied.

Figure 2 is a side view on a larger scale showing the parts of the invention, partly 20 broken away.

Figure 3 is a top plan view of the invention, as applied.

Figure 4 is a section on the line 4—4 Figure 1.

Figure 5 is a detail perspective view of the pulleys located in the angle of the door casing.

The invention has relation to attachments to screen doors, designed to prevent the 30 entrance of flies to the house when the door is opened and, through the agitation of the fan, to cause any flies upon or sufficiently near the door to be shooed out of the open doorway, the object of the invention being 35 an improved device of simple construction and operation.

The invention consists in the novel construction and combinations of parts as hereinafter set forth.

40 In the accompanying drawings illustrating the invention, the numeral 2 designates a screen door, 3 the door casing, and 4 a revolute shoo-fly or fan rotatable in bearings 5 of said casing, the fan being located 45 on the inside of the door casing and screen door.

An upright coiled spring 6 is attached at its lower end to an eye 7 secured to the side of the door casing adjacent to the hinges 50 of the screen door, and to the upper end of the spring is connected a flexible cord or line 8, extending upwardly in a vertical di-

rection or substantially vertical direction and being coiled at 9 once around the rotatable shaft 4' of the fan, thence passing 55 again upwardly over a vertical guide pulley 10 secured to the top of the door casing, and at right angles around a horizontal guide pulley 11 adjacent to the vertical pulley, and then passing horizontally towards 60 the center portion of the doorway, and at right angles around a second horizontal pulley 12 secured to the top of the door casing, and at its end being secured to an eye 13 65 secured to the upper portion of the screen door near the center of the upper rail or frame bar thereof. The adjacent vertical and horizontal pulleys 10 and 11 are preferably mounted upon a single bracket 14.

The invention also acts to automatically 70 close the screen door, once it is opened, and is applicable to screen doors swinging in either direction or hinged at either side.

An ordinary coiled spring such as is commonly used to close screen doors is used in 75 the present case, and is of advantage in that it holds its tension well, and in that the tension may be adjusted to suit conditions by adjusting the length of the cord or line. The spring being located vertically at the 80 side of the door casing at the hinge side is out of the way and will not in any manner disturb passengers going in and out.

An extensible coiled spring pulled out or extended in the opening of the door has 85 been found most efficient in practice, and is preferred to any other form of spring.

We claim:

A screen door closer and shoo-fly attachment, consisting of a horizontal revoluble 90 fan, having its axis parallel to the door and having journal bearings located adjacent to and spaced from the top of the inner side of a door casing, an angular frame adapted to fit into one of the upper corners of the 95 door frame, bearing pins on said angular frame extending at right angles to each other, an upright coiled spring having its lower end secured to the side of said casing adjacent the door hinges, a vertical pulley 100 and a horizontal pulley located adjacent each other and to the hinge side of the door above said fan and mounted upon the said bearing pins, a second horizontal pulley

above said fan, and a flexible cord connected at its lower end to said spring and passing thence directly around the shaft of said fan, thence directly around said adjacent vertical and horizontal pulleys and thence directly around said last named horizontal pulley, and at its other end having connection with the screen door.

In testimony whereof we affix our signatures, in presence of two witnesses.

WILLIAM M. SMITH.
PAUL W. SMITH
